ATTORNEYS.

UNITED STATES PATENT OFFICE.

WILLIAM A. RINGLER, OF PHILADELPHIA, PENNSYLVANIA, ASSIGNOR TO THE GLOBE
WEERNICKE CO., A CORPORATION OF OHIO.

VISIBLE INDEX.

Application filed November 15, 1924. Serial No. 750,045.

This invention relates to card index devices of the so-called visible index type, in which a series of index elements are supported for sliding movement in a frame with the free edges of the elements projecting one beyond the other to expose a narrow marginal edge of each, which exposed marginal edge may carry suitable identification or index characters. The exposed marginal edges of the elements frequently become soiled by repeated handling, and various attempts have been made to protect the exposed edges by transparent sheet material, such as celluloid. In all such cases, it has been customary to merely attach a strip of celluloid over the exposed marginal edge of an element and, therefore, it was necessary either to attach the strip of flexible material after the identification characters were placed on the marginal portion, or the identification was provided upon strips which were placed in pockets formed between the transparent strip and the exposed marginal edge. In the latter case, the strips frequently became detached which caused confusion in identification of the card or element with the missing identification characters. In the former case, the transparent strips must be applied by the user instead of by the factory, which was objectionable.

An object of this invention is to provide an improved visible index device in which the exposed marginal edges of the index elements and units will be effectively protected by transparent sheet material; with which the transparent sheet material may be applied to the elements by the factory or protecting sheets with transparent margins may be provided for attachment by the user at any time; with which the identifying or indexing characters may be applied to the elements by the user in the same manner as if the elements were not protected by the transparent material; with which the transparent material will not interfere with or hinder the use of the index device; and which will be relatively simple, convenient, durable and inexpensive.

A further object is to provide an improved index element protected by transparent material which may be secured to the body of the element in such a manner that it will always remain flat, even though the

body of the element to which it is attached may buckle or warp.

Various other objects and advantages will be apparent from the following description of embodiments of the invention, and the novel features will be particularly pointed out hereinafter in the appended claims.

In the accompanying drawing:—

Fig. 1 is an elevation of a portion of an index device constructed in accordance with the invention; 65

Fig. 2 is an end elevation of an index unit of the same;

Fig. 3 is an elevation of three index units assembled together and illustrating a modification of the invention; 70

Fig. 4 is a sectional elevation of the upper two of the units of the same, with the section taken substantially along the line 4—4 of Fig. 3; and

Fig. 5 is a rear elevation of a corner of one of the units of Figs. 3 and 4, illustrating the details of construction. 75

In the embodiment of the invention illustrated in Figs. 1 and 2, the index element 1 is provided, adjacent one end, with spaced apertures 2 by which it may be attached to the lower pair of arms 3 of the bifurcated opposite ends of a strip 4 of flexible sheet material forming the index element carrier. The apertures 2 of the index element 1 are spaced inwardly from the edge attached to the carrier, and the marginal portion along the attached edge is folded back upon itself as at 5, so as to interlock with the upper edge of the next lower carrier strip and effect the desired spacing between adjacent index elements. In this manner, the index elements 1 will have marginal portions along the free edges exposed for the reception of suitable index or identification characters. A protector element 6, is provided with apertures 7, similar to the apertures 2, and through these apertures, the upper pair of opposite arms 3 of the carrier are passed, so as to support the protector element 6 upon the upper face of the index element 1 which is mounted upon the same carrier. The element 6 may be formed of paper or the like with a strip 8 of transparent flexible sheet material along its free edge, thus providing a transparent marginal free edge which is coextensive with the index element 1 below it, so that the identification char-

105

acters on the exposed marginal edge of that index element will be visible through this transparent marginal portion. The protector element 6 may be swung upwardly to expose the index element beneath it whenever access to the latter is desired, and at the same time, the transparent marginal edge will protect the index element from soiling during the handling of the index 10 elements.

The transparent sheet material may be of celluloid, or other similar material, but inasmuch as such materials do not usually have the same coefficient of expansion as 15 the paper or other material to which they are secured, provision must be made to take care of the difference in expansion, if warping or bulging of the transparent material is to be prevented. If the transparent 20 strip is cemented or attached continuously along the entire edge which is attached to the paper or other material, buckling will inevitably occur. By placing the cement or fastening means only at intervals at a plurality of points along the length of the 25 strip, the paper can bulge slightly between the points cemented or secured to the transparent strip without warping the transparent strip. To facilitate the application of 30 cement only at intervals, either the body part of the element or the transparent strip part is provided with spaced tongues 9 which overlap the other part, and the cement is applied only to the tongues. This 35 considerably facilitates the application of the cement or adhesive whenever an adhesive is utilized.

In Figs. 1 and 2, the tongues are provided upon the edge of the paper body and overlap the transparent strip, and a suitable cement 10 may be applied to the underfaces of the tongues before the application of the transparent strip thereto. Instead of an adhesive coating, the tongues may be attached to the strip by moistening them with a solvent of the transparent material and then pressing them firmly against said strip for a short interval. It will be understood, of course, that mechanical fasteners, such as rivets, may be used to connect the tongues and the transparent strip, if desired.

Referring particularly to Figs. 3 to 5 the transparent protector strip 11 is attached directly to the index element instead of to a separate sheet, the protector strip 11 then acting as the protecting flap for the next adjacent index element. These transparent marginal strips, corresponding to the strips 8, are secured, such as by cement 12 or any 60 other fastening means, at a plurality of spaced intervals along their lengths to the underfaces of the index elements, the attachment being made along the free ends or edges of the elements, so that the transparent marginal edge of each index element

will overlie the exposed portion of the next adjacent index element beneath it. The indexing or identifying characters are placed along the exposed marginal edge of each index element as usual, and this exposed 70 marginal edge will be protected by the overlapping transparent marginal extension of the index element next above it.

It will be observed that by the use of the protecting sheets 6 the exposed marginal 75 edges of the sheets will be visible and effectively protected by the transparent edge portion, and at the same time the entire surface of the index element will be readily accessible for the entry of information or 80 inspection. The protector sheets are made largely of paper which is inexpensive, and such sheets may be removed and applied to new index elements when an old index element is discarded. Where the transparent 85 marginal edge is applied directly to an index element, each element acts as the protecting flap for the next lower index element and the uppermost index element may be protected by a protector element 6 such as shown in Figs. 1 and 2.

In both of the illustrated embodiments of the invention, the transparent protecting strips may be applied to the supporting means by the manufacturer and if index 90 elements without the transparent protecting strips are in use, the protecting elements, shown in Figs. 1 and 2, may be purchased and applied to those elements. In both of the illustrated forms of the invention, the 95 marginal edges of the index elements will be readily accessible for the placing of the indexing characters thereon.

It will be obvious that various changes in the details and materials, which have been 100 herein described and illustrated for the purpose of explaining the nature of the invention, may be made by those skilled in the art within the principle and scope of the invention as expressed in the appended 110 claims.

I claim:

1. In a visible index device, an index element comprising a sheet of paper, and a flat strip of transparent sheet material secured along an edge of the paper sheet so as to provide a transparent marginal extension, the strip of transparent material being secured to the paper sheet adjacent its ends and also intermediate of its ends, 115 being unconnected with the paper elsewhere, so that the paper may buckle or warp slightly without warping the transparent strip.

2. In a visible index device, an index element carrier having bifurcated ends, an index element having spaced apertures through which two of the arms of the bifurcated ends may extend, a sheet of paper having apertures at one end through which the other arms of the bifurcated ends may 125 130

extend, with the paper extending over the index element.

3. In a visible index device, an index element carrier having bifurcated ends, an index element having spaced apertures through which two of the arms of the bifurcated ends may extend, a sheet of paper having apertures at one end through which the other arms of the bifurcated ends may extend, with the paper extending over the index element, said paper strip having along its free end edge a strip of transparent sheet material, forming a transparent marginal extension of the sheet.
4. In a visible index device, a paper index element, and a strip of transparent sheet material cemented to a face of the index element at points adjacent its ends and also intermediate of its ends, being otherwise unconnected to said element, whereby the transparent strip will form a transparent marginal extension of the element, and the paper will be free to buckle intermediate the points of attachment to the strip without warping the strip.

5. In a visible index device, an index

element having a plurality of tongues along one edge, and a strip of transparent sheet material secured to said tongues so as to form a transparent marginal extension 30 of the element.

6. In a visible index device, an index element having a plurality of tongues along one edge and a strip of transparent sheet material cemented to said tongues so as to 35 form a transparent marginal extension of the element.

7. In a visible index device, an index element carrier having tongues, an index element having spaced apertures through 40 which certain of the tongues may extend, a sheet of paper having apertures at one end through which others of said tongues may extend with the paper extending over the index element, said paper strip having 45 along its free end edge a strip of transparent sheet material forming a transparent marginal extension of the sheet, overlying the free marginal edge of the index element.

In witness whereof, I hereunto subscribe 50 my signature.

WILLIAM A. RINGLER.
